[57] CLAIM

The ornamental design of a sagittal saw blade base, as shown and described.

DESCRIPTION

FIG. 1 is a top plan view of a sagittal saw blade base showing my new design, the bottom plan view being a mirror image thereof;

FIG. 2 is a left side elevational view thereof;

FIG. 3 is a right side elevational view thereof;

FIG. 4 is an end elevational view thereof;

FIG. 5 is a top plan view of a sagittal saw blade base showing a modification of my FIGS. 1-4 design, the bottom plan view being a mirror image thereof;

FIG. 6 is a left side elevational view thereof;

FIG. 7 is a right side elevational view thereof; and,

FIG. 8 is an end elevational view thereof.

The broken line showing the cutting portion of the sagittal saw blade is for illustrative purposes only and forms no part of the claimed design.
